United States Patent Office

Des. 193,888
Patented Oct. 23, 1962

193,888

HANDRAILING UNIT OR THE LIKE

Robert V. Gay, Henrico County, Va., assignor to Reynolds Metals Company, Richmond, Va., a corporation of Delaware

Filed Oct. 25, 1960, Ser. No. 62,615

Term of patent 14 years

(Cl. D13—7)

The staircase shown in broken lines is disclosed for illustrative purposes only.

I claim:

The ornamental design for a handrailing unit or the like, as shown and described.
